Inventor

John Cehfus,

By H. R. Willson
Attorney

UNITED STATES PATENT OFFICE.

JOHN CEHFUS, OF ALBANY, NEW YORK.

CLOTHES-LINE CONNECTOR.

SPECIFICATION forming part of Letters Patent No. 543,467, dated July 30, 1895.

Application filed March 20, 1895. Serial No. 542,567. (No model.)

To all whom it may concern:

Be it known that I, JOHN CEHFUS, a citizen of the United States, residing at Albany, in the county of Albany and State of New York, have invented certain new and useful Improvements in Clothes-Line Connectors; and I do declare the following to be a full, clear, and exact description of the invention, such as will enable others skilled in the art to which it appertains to make and use the same.

My invention relates to clothes-line connectors.

The object of my invention is to provide a device of this character by which the sagging of clothes-lines is reduced to a minimum, and which shall be simple of construction, durable in use, and comparatively inexpensive of production.

With these objects in view the invention consists in certain features of construction and combination of parts, which will be hereinafter fully described and claimed.

In the drawings, Figure 1 is a view of a clothes-line showing my improved clothes-line connector applied. Fig. 2 is an edge view of the connector with the jaws open. Fig. 3 is a similar view with the jaws closed. Fig. 4 is a front view showing the position of the lever when the jaws are closed.

1 denotes the jaws of the connector, which are connected at their upper ends and are preferably formed of spring metal, the energy of which is exerted to hold the jaws open.

2 denotes a grooved wheel journaled between the upper ends of the jaws and which is adapted to be supported and roll on the top clothes-line 3. The inner faces of the lower ends of the jaws are provided with transverse registering grooves 4, which are adapted to receive the lower clothes-line 4'.

5 denotes an angle-lever, which is pivoted to the lower end of one of the jaws. This lever is provided with a curved seat 6, which engages a lug 7, projecting from the side of the opposite jaw, which has a slot 8 formed in its lower end to permit of the lever being swung upward and its seat to engage with the lug, as shown in Fig. 3.

In operation, the jaws being open, the device is passed over the top line and its grooved wheel or roller brought into engagement therewith. The lower line, from which the clothes are to be hung, is now passed between the jaws until it is opposite the transverse grooves 4, when the lever 5 is swung upward and locked to the lug 7. The lower line will now be securely supported and its sagging reduced to a minimum.

This device is particularly adapted for pulley-lines—*i. e.*, loop-lines supported by pulleys, as shown in Fig. 1—although it is evident that I may apply the device to fixed lines arranged one above the other.

I have in the present instance shown one connector, but it is to be understood that as many may be employed as desired.

From the foregoing description, taken in connection with the accompanying drawings, the operation of my invention will be readily understood.

By means of my device a person is allowed to stand at one point and by pulling on the line strip it of the clothes, and the clothes will be prevented from trailing on the ground as they are drawn toward the person.

Having thus described my invention, I claim and desire to secure by Letters Patent of the United States—

The combination with two spring jaws, connected at their upper ends and provided with transverse grooves in their inner faces at their lower ends, one of said jaws provided with a slot at its lower end and with a lug on its outer side, a wheel journaled between the upper ends of the jaws, and an angle lever pivoted to the lower end of one of the jaws and provided with a curved seat to engage the lug on the other jaw, substantially as set forth.

In testimony whereof I affix my signature in presence of two witnesses.

JOHN CEHFUS.
